UNITED STATES PATENT OFFICE.

SAMUEL B. WATERS, OF JOHNSTOWN, PENNSYLVANIA, ASSIGNOR TO THE FOWLER RADIATOR AND MANUFACTURING COMPANY, OF SAME PLACE.

DESIGN FOR A RADIATOR-SECTION.

SPECIFICATION forming part of Design No. 29,978, dated January 10, 1899.

Application filed November 16, 1898. Serial No. 696,648. Term of patent 7 years.

To all whom it may concern:

Be it known that I, SAMUEL B. WATERS, of Johnstown, in the county of Cambria and State of Pennsylvania, have invented a new and original Design for a Radiator-Section, of which the following is a specification, reference being had to the accompanying drawing, which forms a part thereof.

The said drawing shows a perspective view 10 of a radiator-section embodying my design.

The leading feature of my design resides in the general conformation of my radiator-section.

The section is a rectangular one, considerably longer in one direction than in the other.

15 1, 2, 3, 4, and 5 are five pipes, of which pipes 1, 2, and 3 extend longitudinally, while the short pipes 4 and 5 lie at right angles to

the long pipes and connect the adjacent ends of the latter. 20 6 and 7 are pipes of smaller diameter, which lie parallel with the short pipes 4 and 5 and connect pipes 1 and 2, respectively, with pipe 3. The connections between pipes 1, 2, 4, and 5 are formed with bulbs 8.

Having thus described my invention, what I claim, and desire to secure by Letters Patent, is—

The design for a radiator-section substantially as shown and described.

In testimony whereof I have affixed my signature in presence of two witnesses.

SAMUEL B. WATERS.
